F. A. REYNOLDS

SAFETY RAZOR BLADE SHARPENING MACHINE

Filed March 6, 1922

INVENTOR,
Frank A. Reynolds
BY Harold R. Stonebraker,
his ATTORNEY

UNITED STATES PATENT OFFICE.

FRANK A. REYNOLDS, OF GENEVA, NEW YORK, ASSIGNOR, BY MESNE ASSIGNMENTS,
TO NONAK STROPPER COMPANY, INC.

SAFETY-RAZOR-BLADE-SHARPENING MACHINE.

Application filed March 6, 1922. Serial No. 541,492.

To all whom it may concern:

Be it known that I, FRANK A. REYNOLDS, a citizen of the United States, residing at Geneva, in the county of Ontario and State 5 of New York, have invented certain new and useful Improvements in Safety - Razor-Blade-Sharpening Machines, of which the following is a specification.

My invention relates to a safety razor 10 blade sharpening machine, and has for its principal object to afford a simple mechanism for quickly and efficiently stropping safety razor blades of various types.

A further purpose of the invention is 15 to afford a construction which is practicable in every regard, and which can be manufactured at a very low cost.

An additional purpose of the improvement 20 is to provide an arrangement which insures accurately positioning a blade with reference to the sharpening element, leaving nothing to the skill of the operator aside from initially positioning and holding the blade and thereafter operating the sharpening 25 element.

Another purpose of the invention is to afford mechanism that is readily adaptable to blades of different types, while always maintaining the blade in a predetermined 30 correct position for most effectively performing the sharpening operation.

An additional object of the improvement 35 is to afford an arrangement in which the blade has a tendency to gravitate toward a sharpening roll, being limited in such movement by positive stop devices, while the necessary pressure for holding the blade against the sharpening roll is imparted by a very slight thumb action, the device being 40 of such a size and form that it can be held in one hand with the thumb of the same hand positioned to maintain the blade against the sharpening roll.

Still a further object of the invention is 45 to construct the machine in such a manner that it can be readily taken apart for cleaning and easily reassembled.

To these and other ends, the invention 50 consists in the improved arrangement and combination of parts that will appear clearly from the following description, in conjunction with the accompanying drawing, the novel features being pointed out in the claims at the end of the specification.

55 In the drawing:

Figure 1 is a plan view illustrating a preferred form of the invention;

Figure 2 is a transverse vertical sectional view on line 2—2 of Figure 1;

Figure 3 is a longitudinal vertical sec- 60 tional view on line 3—3 of Figure 1;

Figure 4 is a perspective view of one of the end walls;

Figure 5 is a perspective view of a portion 65 of the housing, showing the blade support;

Figure 6 is a perspective view of a safety razor blade, of the type for which the blade support shown in Figure 5 is adapted;

Figure 7 is a plan view of a modified 70 form of machine for use with a double edge blade;

Figure 8 is a similar view with the guard thrown back, and

Figure 9 is a transverse vertical sectional 75 view on line 9—9 of Figure 7.

Referring to the construction illustrated in Figures 1 to 6, the device comprises a housing consisting of a body portion 1, which is bent upon itself, with its end walls 2 and 3 forming the top, and terminating 80 in spaced relation to each other to afford a blade-admitting opening 4 through which a blade has access to the sharpening roll. The end portions 2 and 3 are inclined downwardly toward the sharpening roll, affording a V-shaped top on the housing, for a purpose that will appear more clearly presently, and the body portion is held in assembled relationship by means of removable end walls 5 having flanges 6, which overlie the 85 edges of the body portion, the parts being held together by the spindle 7 that removably engages the end walls and is held in position by a knurled nut 8.

9 designates the sharpening roll which is 90 frictionally or otherwise mounted on the spindle 7 so as to turn therewith, and the spindle 7 is preferably bent at one end to afford an operating handle 10. The sharpening roll may be constructed in any desirable way, but is preferably formed with a solid central core, and an exterior leather covering, as set forth in co-pending application, Serial No. 506840, filed October 10, 1921. 100

The blade 11 rests upon the blade support 3, the inclination of the latter causing the blade to gravitate toward the sharpening roll when the machine is held in normal position, and this sliding movement of the 110

blade is limited by suitable stop devices which may be constructed in different ways, depending upon the particular form of blade. In the structure disclosed in Figures 5 to 6, the blade support 3 is cut away to afford flanges 12 bent backwardly upon the body of the blade support, and thereby affording a guideway in which the blade portion 11 slides, while the rear ends of flanges 12 engage the end portions 13 of the blade unit, and thereby hold the blade in a predetermined relationship to the sharpening roll, as illustrated in Figures 1 and 2.

This relative positioning of the blade to the sharpening roll is determined by the angle of inclination of the blade support, and the position of the stop devices 12, and is such that when the blade is in its final position, and is pressed slightly toward the sharpening roll, it will assume the proper tangential relationship for most effective cooperation with the sharpening roll. The blade support 3 preferably terminates at a point in juxtaposition to the sharpening roll, as illustrated in Figure 2, and is slightly yieldable in order to bring the blade against the roll under pressure. The necessary pressure for this action is created by the thumb of the operator, who holds the device 15 in one hand, placing the thumb of the same hand in the V-shaped top of the housing, where it easily and comfortably rests. The necessary pressure is readily afforded by moving the thumb against the blade 11 when 20 the latter is positioned as shown in Figure 1, and pressing the thumb slightly toward the sharpening roll to obtain whatever tension is desirable between the blade and the sharpening roll. The blade is sharpened 25 first on one side, and is then reversed on the blade support to sharpen the opposite side of the edge.

The structure thus far described is adapted more particularly for single edged blades, 45 and those of considerable stiffness, and for blades which are quite flexible, and have double edges, I provide a structure such as illustrated in Figures 7 to 9 inclusive. The blade shown in this embodiment, and designated at 13, is very thin and provided with openings 14. To accommodate this type, I provide the blade support with projecting lugs 15, which pass through the openings 14 and retain the blade in proper position on 50 the support. In order to protect the hand of the operator against the rear edge of the blade, I employ a guard member 16 which is hinged to the ears 17, and when thrown to the position shown in Figure 9, entirely 55 covers the rear edge of the blade. The guard member also performs the additional function of pressing the blade uniformly throughout its entire length against the sharpening roll. With blades constructed 60 very thin, if thumb pressure is applied di-

rectly against the blade, there might be a tendency of the blade to buckle slightly, causing it to contact with the sharpening roll at one point more than at another, and this is entirely obviated by having the free edge of the guard member, designated at 18, contact evenly with the blade throughout its length. In operating this form of the machine, after the blade is positioned and the guard member adjusted to the position shown in Figure 9, the necessary pressure is had by placing the thumb against the upper surface of the guard member, and forcing it lightly against the blade, while at the same time turning the sharpening roll. The guard member is provided with corrugations 19 on its upper surface, which enable engaging it more readily, either during the sharpening operation, or when throwing the guard back to its inoperative position when the blade is to be removed, such position of the guard being illustrated in Figure 8. In order to permit convenient removal of a blade of this type, the housing is cut away at 20 to provide an opening which permits a finger to be inserted under the blade so as to lift the latter off from the projections 15.

While I have described the invention with reference to certain more or less particular embodiments, it is not limited in its application to the detailed arrangements set forth, as other modifications are within the province of my improvement, and this application is intended to cover any changes or departures coming within the intended purposes of the invention or the scope of the following claims.

I claim:

1. A safety razor blade sharpening machine comprising a housing, and a sharpening roll journaled in the housing, said housing having a V-shaped top affording oppositely inclined walls with an opening at the centre to admit a blade against the sharpening roll, one of said inclined top walls constituting a support for the blade, said V-shaped top acting to receive the operator's thumb and permit pressing the blade against said roll.

2. A safety razor blade sharpening machine comprising a housing including removable end walls, a sharpening roll in the housing, a spindle removably engaging said sharpening roll and the end walls of the housing and acting to retain the sharpening roll and end walls in place, and means for supporting a blade adjacent to the sharpening roll.

3. A safety razor blade sharpening machine comprising a housing, and a sharpening roll journaled in the housing, said housing embodying an integral body portion bent upon itself with its end portions forming the top and inclining from opposite sides downwardly toward the sharpening roll, the ex-

5 tremities of said end portions being spaced from each other to afford a blade-admitting opening and one of said inclined top walls affording a support for a blade, and end walls removably engaging the edges of said body portion and having flanges overlying the same.

10 4. A safety razor blade sharpening machine comprising a housing, and a sharpening roll journaled in the housing, said housing embodying an integral body portion bent upon itself with its end portions forming the top and inclining from opposite sides downwardly toward the sharpening roll, the extremitiess of said end portions being spaced from each other to afford a blade-admitting opening and one of said inclined top walls affording a support for a blade, separate end walls engaging the edges of said body portion, and a spindle removably engaging said end walls and sharpening roll and acting to hold the parts together.

15 5. A safety razor blade sharpening machine comprising a housing, and a sharpening roll journaled in the housing, said housing having a V-shaped top affording oppositely inclined walls with an opening at the centre to admit a blade against the sharpening roll, one of said inclined walls serving

30 to support a blade with its edge against the sharpening roll, and a guard member carried by the housing and positionable to prevent contact with the outer edge of a blade during the sharpening operation, said V-shaped top acting to receive the operator's thumb 35 and permit pressing the blade against said roll.

35 6. A safety razor blade sharpening machine comprising a housing, and a sharpening roll journaled in the housing, said housing having a V-shaped top affording oppositely inclined walls with an opening at the centre to admit a blade against the sharpening roll, one of said inclined walls serving to support a blade with its edge against the sharpening roll, and a guard member carried by the housing and positionable to prevent contact with the outer edge of a blade during the sharpening operation, said guard member also being operable against the 40 blade so as to exert an equal pressure against the latter throughout its length, said V-shaped top acting to receive the operator's thumb and permit pressing the blade against said roll. 50

55 In witness whereof, I have hereunto signed my name.

FRANK A. REYNOLDS.
